DESIGN FOR A CLIP FOR MIRRORS OR
GLASS PANELS

Earle W. Clark, Grand Rapids, Mich., assignor to
Keeler Brass Company, Grand Rapids, Mich.,
a corporation of Michigan

Application May 16, 1947, Serial No. 139,078

Term of patent 14 years

(Cl. D54—9)

To all whom it may concern:

Be it known that I, Earle W. Clark, a citizen of the United States of America, residing at Grand Rapids, in the county of Kent and State of Michigan, have invented a new, original, and ornamental Design for a Clip for Mirrors or Glass Panels, of which the following is a specification, reference being had to the accompanying drawing, forming part thereof, in which:

Fig. 1 is a front perspective view, and

Fig. 2 is a rear perspective view of a clip for mirrors or glass panels, showing my new design, the sides not illustrated being the same as the sides illustrated.

I claim:

The ornamental design for a clip for mirrors or glass panels, as shown and described.

EARLE W. CLARK.
